FASTENER

Robert C. Legat, New Britain, Conn., assignor to The G. E. Prentice Mfg. Co., Kensington, Conn., a corporation of Connecticut

Application June 26, 1952, Serial No. 295,599

4 Claims. (Cl. 24—206)

This invention relates to devices used for fastening together two parts of an article such as the uppers of an overshoe.

Overshoes are usually secured in place by means of a ladder-like member and a clasp which engages with the member. The usual type of clasp employed on overshoes essentially comprises a plate to which is pivotally connected a spring-pressed finger piece adapted to be inserted up through the spaces in the ladder-like member and then moved to a closed position over the plate. This type of clasp has been used on overshoes for a great many years without substantially change and while it is an efficient fastener, it possesses certain disadvantages which render its use not entirely satisfactory. This is primarily due to the fact that it must be connected by inserting the finger piece through the openings of the ladder-like member from beneath the latter. This is not an easy operation and is especially difficult when the overshoes are wet or stiff or the hands cold or when gloves are being worn. Further, under such conditions, it is also difficult to unfasten the clasp, especially when the parts thereof are frozen or clogged with snow.

The primary purpose of the present invention is to provide an improved fastener of the indicated type which shall be much simpler to work and which shall overcome the aforesaid disadvantages of the type of fastener now employed on overshoes.

Other advantages and the novel features of the present invention will become apparent after a perusal of the following description when read in connection with the accompanying drawings, in which:

Fig. 1 is a top plan view of the ladder-like member forming part of the fastener;

Fig. 2 is a top plan view of the hook or clasp part of the fastener with the lever shown in unlatched position;

Fig. 3 is a top plan view showing the devices of Figs. 1 and 2 engaged;

Fig. 4 is a vertical sectional view taken along the line 4—4 of Fig. 3;

Fig. 5 is a side elevational view of the structure shown in Fig. 3;

Fig. 6 is a bottom plan view of the hook or clasp with the lever in unlatched condition, and

Fig. 7 is a vertical sectional view of the hook or clasp part in unlatched condition.

In the drawings, the ladder-like member is designated generally by the reference numeral 10. The ladder or catch-plate 10 is of ordinary construction, being preferably formed from sheet metal and composed of a plurality of openings 11 separated by rungs or bars 12. Provided at the inner end of the ladder 10 is an opening 13, through which a portion of the shoe upper extends to connect such member to the shoe, as is indicated in Fig. 4 of the drawings. It will also be noted from such figure, that the rungs or bars 12 are substantially rectangular in cross section and that the member 10 is arcuately-shaped to better conform to the foot of the wearer.

The clasp 15 of the fastener is also formed from sheet

2

metal and is composed of a plate-like portion 16 provided with an opening 17 through which a portion of the shoe upper extends to connect such device to the shoe (note Fig. 4). The plate 16, which is also arcuately-shaped as shown in Fig. 4, is slit along its side edge portions from the outer end thereof to points located at approximately one-third its length to provide two tongues which are rolled back upon themselves to provide bearing sockets 18, 18, for a pivoted lever 19. The lever 19 is pivotally connected to the plate 16 by integrally formed trunnions 20 which extend outwardly into the sockets 18.

The reduced portion 21 of the plate 16 projecting beyond the sockets 18 is stiffened and strengthened by ribs 22 which extend in diverging relation into the main portion of the plate 16 to points adjacent to the aperture 17 of such plate. The outer end of plate portion 21 is provided with a centrally located extension 23 which is turned back beneath such portion 21 to form a hook. The hook 23 has a width slightly less than the width of the openings 11 so that it may be readily inserted through an opening 11 from the top or convex side of the member 11 and caught on to one of the bars 12 of such member. The form of the hook is such that it may readily be caught on to a bar 12 and will release freely when the overshoe is tight on the foot of the wearer. Stamped out of the plate 16 between the ribs 22, is a centrally located, longitudinally extending tongue 24 whose connected end is adjacent to the inner ends of the ribs 22 and whose outer free end is located within the area of the plate portion 21. The tongue 24 is formed to have a greater degree of curvature than the plate 16, so that in its normal condition in the region of the sockets 18, it is slightly above the tops of the ribs 22. The outer free end of the tongue 24 is bent upwardly to provide a locking member 25 for locking the hook 23 in position on a bar 12. It will be noted from Fig. 4 of the drawings, that the locking member 25 is so constructed and arranged that when the tongue 24 is depressed, such member 25 is spaced from the inner end of hook 23 a distance only slightly greater than the width of a bar 12 and presents a transversely disposed stop against movement of the bar 12 relative to the hook 23. Thus, the member 25 effectively locks the hook 23 in position on the bar 12 until the tongue 24 is enabled to return by its own resiliency to normal position.

The means for depressing the tongue 24 to accomplish the aforesaid locking action is the lever 19 which has an actuating arm 26 whose free end is bent to provide a suitably shaped fingerpiece and which has an actuating arm 27 extending at right angles, or approximately so, to the arm 26 and located at or near the lugs or trunnions 20 of such lever. When the lever 19 is raised, the arm 27 exerts no pressure on the tongue 24 and the member 25 on such tongue is in a raised or retracted position. In its retracted condition, the member 25 is located above the plate portion 21, whereby the hook 23 can be freely removed from or attached to the ladder 10. When the lever 19 is depressed as shown in Fig. 4 of the drawings, the tongue 24 is depressed to cause the member 25 thereof to move through the opening formed in the plate portion 21 and across the opening of the hook 23, to lock the clasp 15 to the ladder 10.

From the foregoing description, it is believed to be clear that when the arm 26 of the lever 19 is raised, the hook 23 may be readily connected to any one of the bars 12 of the ladder 10 by passing it through one of the openings 11 thereof from the top. When the hook 23 engages a bar 12, the finger-piece or arm 26 of the lever is depressed to lock the parts together. The clasp 15 may be detached from the ladder 10 by simply lifting the arm 26 of the lever, the parts then readily separating without the necessity of great effort or any manipulation.

While I have described and illustrated a preferred form of my invention, it will be evident to those skilled in the art that various changes and modifications may be made therein without departing from the spirit of the invention or the scope of the appended claims.

I claim:

1. A fastening device for use with a ladder-like catch plate, comprising a body plate formed to lie prostrate on said catch plate and having integral with one end thereof a reduced turned under, quiescent hook adapted to be inserted into an opening between the bars of said catch plate and to hook onto a bar thereof while the body plate is lying on but moved relative to said catch plate, a longitudinally extending tongue cut out of the material forming the central portion of said body plate and positioned substantially in the plane of said body plate, said tongue having its free end adjacent to said hook, the free end of said tongue being bent outwardly to extend transversely of said body plate and said bent end being spaced from the curved end of said hook a distance slightly greater than the width of the bars on said catch plate, an operating lever extending transversely of said tongue intermediate the ends thereof, means on the outer sides of said body plate for pivotally supporting said lever, said lever having an actuating arm engageable with an intermediate portion of said tongue and a finger piece operable to pivot said lever to cause the actuating arm thereof to depress the free end of the tongue below said body plate so as to move the bent end thereof through an opening in said catch plate adjacent to the one through which said hook has been inserted into position to lock the hooked bar of said catch plate between said apertures in said hook.

2. A fastening device for use with a ladder-like catch plate, comprising a body plate formed to lie prostrate on said catch plate and having integral with one end thereof a reduced, turned under, quiescent hook adapted to be inserted into one opening between the bars of said catch plate and to hook onto a bar thereof while the body plate is lying on but moved relative to said catch plate, a longitudinally extending tongue cut-out of the material forming the central portion of said body plate and positioned substantially in the plane of said body plate, said tongue having its free end normally positioned above said catch plate adjacent to said hook and spaced from the curved end of said hook a distance slightly greater than the width of the bars on said catch plate, an operating lever extending transversely of said tongue intermediate the ends thereof, means on the outer sides of said body plate for pivotally supporting said lever, said lever having an actuating arm engageable with an intermediate portion of said tongue and a finger piece operable to pivot said lever to cause the actuating arm thereof to depress the free end of the tongue below the body plate and through an opening in said catch plate adjacent to the one through which said hook has been inserted to a position to lock the hooked bar of said catch plate between such apertures in said hook.

3. A fastening device for use with a ladder-like catch plate, comprising a body plate formed to lie prostrate on said catch plate and having the forward end portions of its side ends turned back over said body plate to provide a pair of spaced, aligned bearing sockets intermediate the ends of said body plate, a lever having trunnions mounted in said sockets and having an actuating arm and a finger piece operable to pivot said lever about its trunnions, a

turned under, quiescent hook integral with the reduced forward end of said body plate, and formed to be inserted into an opening between the bars of said catch plate and to hook onto a bar thereof while the body plate is lying on but moved relative to said catch plate, a longitudinally extending tongue cut out of the material forming the central portion of said body plate and positioned substantially in the plane of said body plate, said tongue being integrally connected to the enlarged part of said body plate and extending beneath said lever and between said bearing sockets and into the reduced forward end of said body plate so that said lever extends transversely over an intermediate portion of said tongue, the free end of said tongue being normally positioned above said catch plate adjacent to said hook and spaced from the curved end of said hook a distance slightly greater than the width of the bars on said catch plate, said lever being operable to cause the actuating arm thereof to engage an intermediate portion of said tongue and thereby to depress the free end of the tongue below the body plate and through an opening in said catch plate adjacent to the one through which said hook has been inserted to a position to lock the hooked bar of said catch plate between such apertures in said hook.

4. A fastening device for use with a ladder-like catch plate, comprising a body plate formed to lie prostrate on said catch plate and having integral with one end thereof a reduced, turned under, quiescent hook adapted to be inserted into an opening between the bars of said catch plate and to hook onto a bar thereof while the body plate is lying on but moved relative to said catch plate, a longitudinally extending tongue cut out of the material forming the central portion of said body plate and positioned substantially in the plane of said body plate, said tongue having an intermediate portion bent outwardly and its free end adjacent to said hook, the free end of said tongue being bent outwardly so as to be disposed at substantially right angles to the body of said tongue and said bent end being spaced from the curved end of said hook a distance slightly greater than the width of the bars on said catch plate, an operating lever extending transversely of said tongue over the bent intermediate portion thereof, means on the outer sides of said body plate for pivotally supporting said lever, said lever having an actuating arm engageable with the bent intermediate portion of said tongue and a finger piece operable to pivot said lever to cause the actuating arm thereof through its engagement with said bent intermediate tongue portion to move said bent free end of the tongue through said body plate and through an opening in said catch plate adjacent to the one through which said hook had been inserted to a position to lock the hooked bar of said catch plate between said apertures in said hook.
